UNITED STATES PATENT OFFICE.

DEWALDEN L. BROWN, OF FRANKLIN, MASSACHUSETTS.

HOISTING-GEAR.

SPECIFICATION forming part of Letters Patent No. 389,052, dated September 4, 1888.

Application filed June 16, 1888. Serial No. 277,293. (No model.)

To all whom it may concern:

Be it known that I, DEWALDEN L. BROWN, of Franklin, in the county of Norfolk, State of Massachusetts, have invented a certain new and useful Improvement in Hoisting-Gears, of which the following is a description sufficiently full, clear, and exact to enable any person skilled in the art or science to which said invention appertains to make and use the same, reference being had to the accompanying drawings, forming part of this specification, in which—

Figure 1 is a top plan view of my improved hoisting-gear, the rope being represented as taut; and Fig. 2, a vertical section taken on line *x x* in Fig. 1, certain of the parts being shown in side elevation and the rope being represented as slack.

Like letters and figures of reference indicate corresponding parts in the different figures of the drawings.

My invention relates to that class of hoisting-gear which is employed in derricks, on shipboard, in warehouses, &c., for raising blocks of stone, anchors, bales of goods, and other heavy bodies; and it consists in certain novel features, as hereinafter fully set forth and claimed, the object being to produce a simpler, cheaper, and more effective device 30 of this character than is now in ordinary use.

The nature and operation of the improvement will be readily understood by all conversant with such matters from the following explanation:

In the drawings, A represents the windlass; B B, the standards or supports in which the windlass is journaled, and C a rope or cable.

The standards may be arranged vertically, horizontally, or in any other suitable position, 40 it being understood that they are to be firmly secured to proper supports.

Two ratchet-wheels, 15, are attached to the windlass, one adjacent to each of the standards B, the teeth of said wheels inclining in the same direction. A triangular plate, D, is connected with the inner face of each of the standards B by a screw-bolt, 25, which passes through an elongated outwardly-curved slot, 35, in said plate, said slot constituting the arc of a circle of which the windlass A is the center. The lower edge of the plate D is cut out

or curved, as shown at 45, the curves of the slot 35 and said edge being in parallelism with each other. Attached to the forward lower corner of each of the plates D, as viewed from the right in Figs. 1 and 2, there is an actuating-pawl, 55, adapted to engage the teeth of the ratchet-wheel 15, and pivoted to the opposite corner of each of said plates there is a brake-shoe, 65. A screw-bolt, 75, is inserted in each of the standards B beneath the curved edge 45 of the plate D, said bolts acting as fulcrums for the plates when oscillated to rotate the windlass, the bolts 25 and 75 being so arranged with respect to each other that a vertical line drawn through the bolt 75 will be slightly nearer the windlass than a vertical line drawn through the bolt 25 when the windlass is arranged as shown in the drawings. A detachable lever, E, is inserted in a socket in 70 the outer end of each of the plates D for rocking or oscillating said plates. A recess, 85, is formed in the plate D at the forward end and lower side of the slot 35 for receiving the bolt 25, as hereinafter described.

Secured to the windlass A, at either side of each of the ratchet-wheels 15, there is a disk, 95. These disks are slightly greater in diameter than the ratchet-wheels, their peripheries projecting beyond the teeth of said 80 wheels and serving as friction-drums on which the brake-shoes act, each of said shoes being wide enough to span two of the disks and one of said ratchet-wheels and kept out of contact with the wheels by the drums.

In the use of my improved gear the plates D are alternately moved back and forth on their supports by the levers E, their pawls 55 alternately engaging and releasing the teeth of the ratchet-wheels 15, and rotating the windlass in a manner that will be readily understood by all conversant with such matters without a more explicit description.

In drawing the plates forward, when it is desired to merely wind up the cable or rope 95 on the windlass, the plates are not advanced sufficiently to permit the bolt 25 to drop into the recess 85; but by drawing either of the plates forward sufficiently to permit the bolt 25 to drop into the recess 85 the pawl 55 will 100 be detached from the teeth of the ratchet-wheel 15 and the brake-shoe 65 brought into contact

with the peripheries of the disks 95 at either side of said wheel, thereby enabling the drum A to be controlled and the rope to be "slackened" and the article being raised to be lowered at any speed desired.

Drums H are mounted on the outer ends of the windlass on which ropes or cables may be wound.

One plate, D, may be omitted, if desired, 10 and a retaining-pawl used to hold the windlass while moving the actuating-pawl forward to take a new hold.

A pin, 14, is employed to hold the plate D and enable the lever E to be released without 15 without permitting the windlass to be turned back.

Having thus explained my invention, what I claim is—

1. In a device of the character described, a 20 windlass journaled in standards or supports, a ratchet-wheel and a friction-disk secured on said windlass, a plate having its inner edge curved and provided with a curved slot in its body in parallelism therewith and having a 25 lateral recess at one end of said slot for receiving the supporting-pin, an actuating-pawl on said plate, a brake-shoe pivoted to said plate, a lever for oscillating said plate, and two bolts, one of which passes through said 30 slot into a support for the plate and the other into said support adjacent to the curved edge of the plate, said plate being so arranged that its actuating-pawl will engage the ratchet-wheel on the windlass and its brake-shoe the

friction-disk on the windlass, substantially as 35 set forth.

2. In a device of the character described, the windlass A, provided with the ratchet-wheels 15 and disks 95, the standards B, in which said windlass is journaled, the plates 40 D, provided, respectively, with the curved edges 45, curved slots 35, recesses 85, and pawls 55, the brake-shoes 65, pivoted to said plates, the bolt 25, inserted in said slots and secured to the standards D, the bolts 75, secured to the standards D, and so disposed as to respectively engage the curved edges 45 of the plate D, and the levers E for said plates, all being combined and arranged to operate substantially as specified. 50

3. In a device of the character described, the windlass A, provided with the ratchet-wheels 15 and disks 95, the standards B, in which said windlass is journaled, the plates D, provided, respectively, with the curved edges 45, curved slots 35, recesses 85, and pawls 55, the brake-shoes 65, pivoted to said plates, the bolt 25, inserted in said slots and secured to the standards D, the bolts 75, secured to the standards D, and so disposed as 55 to respectively engage the curved edges 45 of the plate D, the levers E for said plates, and the pin 14, all being combined and arranged to operate substantially as set forth. 60

DEWALDEN L. BROWN.
